UNITED STATES PATENT OFFICE.

WILLIAM W. HAWKINS, OF BROOKLYN, NEW YORK, ASSIGNOR TO WEBSTER ELECTRIC COMPANY, OF RACINE, WISCONSIN, A CORPORATION OF WISCONSIN.

IGNITION MAGNETO.

Application filed March 11, 1922. Serial No. 542,929.

To all whom it may concern:

Be it known that I, WILLIAM W. HAWKINS, a citizen of the United States, and resident of Brooklyn, in the county of Kings and State of New York, have invented a certain new and useful Improvement in Ignition Magneto, of which the following is a full, clear, concise, and exact description, reference being had to the accompanying drawings, forming a part of this specification.

This invention relates to magnetos of the type which are commonly employed with internal combustion engines for ignition purposes.

The object of the invention is to provide a magneto of this character which will generate an exceedingly intense spark yet will not be complicated in its construction and will consist of relatively few parts.

One of the features of the present invention is the arrangement of the transformer core with its ends adjacent to inductor elements carried at opposite ends of the magneto rotor.

Another feature of the invention resides in the circuit arrangement interconnecting the generator coil and the primary coil of the transformer with the interrupter whereby the advantages of the mechanical construction herein set forth are utilized.

Other features and advantages will appear from time to time as the description of the invention progresses.

35 In the drawings,

Figure 1 is a vertical sectional view taken substantially on the line 1-1 of Figure 2;

Figure 2 is a section taken substantially on the line 2-2 of Figure 1;

40 Figure 3 is a perspective view of the rotor armature detached;

Figure 4 is a section taken substantially on the line 4-4 of Figure 1;

Figure 5 is a section taken on the line 5-5 of Figure 1;

45 Figure 6 is a schematic perspective view of the rotor, permanent magnet pole pieces and ends of the transformer core, showing the relative relations of the several parts, and

Figure 7 is a diagrammatic illustration of circuit employed with the device.

In the drawings, in which like parts in the several views are indicated by the same reference characters, 10 indicates the permanent

magnets, which are of the usual horse-shoe or U-shape, and are mounted side by side so as to be, in effect, a single magnet. The magnets 10 are provided with the usual laminated pole pieces 11 and 12. The magnets 10 and pole pieces 11 and 12 are secured in position by the base portions 13 and 14, which, if desired, may be formed by casting, in the usual manner, the only requirement being that a cylindrical opening be provided between the pole pieces 11 and 12 within which may be mounted the rotary element of the magneto.

Secured to the remote edges of the magnets 10 and the base members, in any desired manner, are the end cover plates 15 and 16. The cover plate 15 is provided with an opening 17 through which projects one end of the rotor shaft 18. Cover plate 15 is also provided with an annular recess in which is mounted the ball bearing 20. The cover plate 16 is provided with an opening 21 through which projects the collar 22 on the shaft 18. The plate 16 is provided also with an annular recess 23 within which is mounted the ball bearing 24 for the opposite end of the shaft 18.

Rigidly secured to the shaft 18 substantially midway between the bearing members 20 and 24 is the laminated rotor armature 25 which may be of the usual "H" type. On the armature 25 are the generator coils 26. Coils 26 are arranged in series, and are, in effect, a single coil.

Rigidly secured to the shaft 18, in any desired manner, adjacent to the bearings 20 and 24, respectively, are the cylindrical supporting members 27 and 28. Mounted with in the outer periphery of the supporting member 28 are the arcuate laminated inductor elements 29 and 30. These inductor elements are symmetrically positioned on opposite sides of the support 28, and each extends through an arc of substantially 90°. Mounted within the periphery of the support 27 is a similar pair of laminated inductor elements 31 and 32, which are of substantially the same size as those associated with the support 28, and likewise are symmetrically arranged at opposite sides of the support 27. The inductor element 32 is, however, arranged slightly in advance of the inductor element 30, as shown in Fig. 6.

The inductor element 31 is arranged in advance of the inductor element 29 in the same

way that inductor element 32 is in advance of the inductor element 30.

Mounted in the space within the upper portion of the magnets 10 is a transformer comprising the core piece 33, primary coil 34 and the secondary coil 35. Secured to the opposite ends of the core piece 33 and extending downwardly therefrom are the core piece extensions 36 and 37. The extension 36 has its free end adjacent to the path of the inductor segments 29 and 30, while the free end of the extension 37 is adjacent to the path of the inductor segments 31 and 32.

Extending through the laminations forming the rotor armature 25, at the opposite ends thereof, are the pins 38 and 39. The ends of each of the pins 38 and 39 are received by openings in the adjacent surfaces of the supporting elements 27 and 28, respectively. Spacing sleeves 40 are mounted about the pins 38 and 39 between the remote sides of the armature member 25 and the supporting members 27 and 28.

Mounted about the right end of the shaft 18, as seen in Fig. 1, with its free edges in sliding engagement with the outer surface of the offset portion 23 of end 16 is a housing member 41. In screw threaded engagement with the end of the housing member 41 is the cover member 42 of insulating material. Projecting outwardly from the base member 13 is a post or standard 43, provided at its outer end with the spring finger 44 which is adapted to engage the outer surface of the cap member 42 and maintain the housing in position. The interrupter contacts are mounted on the housing member 41.

Referring to Fig. 5, it will be noted that the movable interrupter contact arm 45 is pivotally supported on the link 46, which in turn is mounted in the inwardly projecting flange 47 of the housing member 41.

The movable contact arm 45 is provided intermediate its ends with the projecting lug 48 of insulating material which may be secured to the arm, in any desired manner. The arm 45 at its end remote from the link 46 is provided with the contact element 49 arranged to engage the fixed contact 50 adjustable in the mounting 51, which is insulatively secured to the housing member 41, in any desired manner. A spring 52 has one end encircling the pin 53 projecting from the flange 47, and the other end engaging the arm 45 adjacent to its free end, thus maintaining the contact 49 in engagement with the fixed contact 50.

Secured to the shaft 18, by means of the nut 54, is the interrupter cam 55 which is provided at diametrically opposite sides thereof with cam projections 56 adapted, upon rotation of the shaft 18, to operatively engage the lug 48. Thus, it will be noted

that the contacts 49 and 50 are normally held in engagement but are separated from each other by the co-operation of the cam projections 56 with the lug 48 twice during each revolution of the rotor shaft.

One end of the coil 26 is grounded to the frame of the machine. The other end of the coil is conductively joined to the rod 57, which is insulatively mounted within the shaft 18, in the usual manner. A spring finger 58 is joined at one end to the fixed contact supporting member 51 and has its other end in engagement with the projecting end of the rod 57 when the housing member 41 is in operative position.

Extending through the cap member 42 is a binding post 59 provided with the nut 60, by means of which the conductor 61 extending to one end of the primary coil 34 may be joined to the binding post 59. Slidably mounted on the inwardly projecting end of the binding post 59 is a collar 62 which is adapted to be held in firm engagement with the spring finger 58 by means of the bow spring 63. Thus, it will be seen that when the housing 41 is in position, as indicated in Fig. 1, the non-grounded end of the coil 26 will be conductively connected to the binding post 60 and through the conductor 61 to the non-grounded end of the primary winding 34. Due to the fact that the spring finger 58 is in electrical engagement with the rod or core 57, the insulated stationary contact 50 of the interrupter is also connected to the non-grounded ends of the primary coil 34 and generating coil 26, as shown in Fig. 7. As previously explained, the movable contact arm 45 of the interrupter is connected to ground. The secondary coil 35 has one end connected to ground or to the frame of the magneto, while the other end is connected to a distributor, spark plug or similar device.

A condenser 63 is provided in parallel with the interrupter contacts 49 and 50. The condenser 63, as shown in Figs. 1 and 2, may be mounted in a depression in the base member 14. A cover strip 64, of any desired flexible material, may be provided over the top and on the sides of the magneto and secured to the base member 13 by screws or other devices, as shown in Figs. 1 and 2.

The operation of the device will now be described, reference being had particularly to Figs. 6 and 7. We will assume that the rotor is substantially in the position shown in Fig. 6, when the rotor armature 25 will be arranged substantially horizontally, as indicated in Fig. 2. At this time, the maximum flow of flux will extend through the member 25 and, therefore, through the coils 26. If, now, the rotor shaft 18 is rotated in a counterclockwise direction, as viewed in Fig. 6, the flux extending through the coils 26 will be decreased. As the rotor con-

tinues its counterclockwise movement, the inductor segment 32 comes into a position to complete a path between the pole piece 12 and the end 37 of the transformer core 33. 5 The segment 30 at the opposite end of the rotor will now be in a position to bridge the gap between the pole piece 11 and the opposite end 36 of the transformer core, and flux will now flow through the extensions 36 and 37 and core piece 33, thus tending to short circuit the rotor element 25, and causing a still further decrease in the flux extending through the coils 26. The rapid decrease in the flux through the coils 26 sets up a surge of current, but as the interrupter contacts 49 and 50 are now in engagement, the coil 26 is in a closed circuit and the surge of current has no effect.

At the instant when approximately the maximum flow of flux extends through the core 33, the interrupter contacts 49 and 50 will be caused to open by the engagement of one of the interrupter elements 56 with the lug 48. The coil 26 is no longer in a closed circuit, and the surge of current set up in the coil 26 will now find an outlet through the primary coil 34 of the transformer. The impulse of current from the generating coil will be augmented by the discharge 25 from the condenser 63. The coil 34 will be so wound on the core 33 that the surge of current from the coil 26 will act to oppose the flux flowing through the core 33, thus causing a rapid reversal in the magnetic lines extending through the core 33, and setting up a high potential surge of current in the secondary winding 35.

While the manner of operation above described is the preferred arrangement, yet the device will give satisfactory results if the coil 34 is wound on the core 33 in the opposite direction, that is, in a direction such that the surge of current from the coil 26 and condenser 63 will act to augment the flux which is caused to flow through the core 33, due to the inductor segments 30 and 32 bridging the gaps between the pole pieces 11 and 12 and the ends 36 and 37, respectively. With the primary coil 34 arranged in this manner, the surge of current from the generator coil 26 at the time the contacts 49 and 50 are opened, will hasten the building up of the flux in the core 33, and will cause the core 33 to become thoroughly and quickly saturated, thus creating a high potential impulse of current in the secondary coil 35. With this arrangement of the coil 34, it is believed the interrupter contacts should be open slightly sooner than with the previously described arrangement, in order to get the best results.

While in the drawings and in the above description, certain definite details and relations of parts have been set forth, it is to be understood that modifications are con-

templated by applicant, and that the invention is to be limited merely by the scope of the appended claims.

Having now described my invention, what I claim is new and desire to secure by Letters Patent of the United States is:

1. In a magneto, a rotor, a generator coil on said rotor, magnet pole pieces, a transformer coil, a core for said transformer coil, the ends of said core being adjacent to the path of said rotor at the opposite ends thereof but separated from said magnet pole pieces, and means carried by said rotor for completing paths from said pole pieces to the ends of said core respectively. 80

2. In a magneto, a rotor, a generator coil on said rotor, magnet pole pieces, a transformer coil, a core for said transformer coil magnetically spaced from said pole pieces and inductor segments comprising part of said rotor arranged to complete paths from said pole pieces to the said core respectively. 85

3. In a magneto, a rotor, a generator coil or said rotor, magnet pole pieces, a transformer coil, a core for said transformer coil, the ends of said core being adjacent to the path of said rotor at the opposite ends thereof, and inductor segments comprising part of said rotor arranged to complete paths from said pole pieces to the ends of said core respectively, said segments forming the sole means magnetically linking said core with said pole pieces. 90

4. In a magneto, a rotor, a generator coil on said rotor, magnet pole pieces, a transformer coil, a core for said transformer coil, magnetically isolated from said pole pieces, means carried by said rotor for simultaneously completing paths from said pole pieces to the ends of said core respectively, and an interrupter for said generator coil. 100

5. In a magneto, a rotor, a coil on said rotor, magnet pole pieces, a second coil, a core for said second coil, inductor segments comprising a part of said rotor arranged to simultaneously complete paths from said pole pieces to the ends of said core respectively, a circuit joining the end of one of said coils to the end of the other coil, and an interrupter for controlling the flow between said coils. 110

6. In a magneto, a rotor armature, a generator coil on said armature, magnet pole pieces, a transformer coil, a core for said transformer coil, the ends of which core are separated from said pole pieces, and inductor segments fixed to said rotor armature at opposite sides thereof and in angularly offset relation to simultaneously complete paths from said pole pieces to the ends of said core respectively. 120

7. In a magneto, a rotor including an armature, a coil on said armature one end of said coil being grounded, magnet pole pieces, 125

- a second coil, one end of said second coil being grounded, a core for said second coil, inductor segments mounted at opposite ends of said rotor armature and arranged to simultaneously complete paths from said pole pieces to the ends of said core respectively, a circuit joining the non-grounded ends of said coils, and an interrupter for controlling the flow between said coils.
- 5 10 8. In a magneto, pole pieces, a rotor armature, a coil, a core for said coil, said parts being arranged so that in one position of said rotor, said armature forms a path between said pole pieces, and in another position forms a path between one of said pole pieces and one end of said core, a coil about said armature, said coils being in a series circuit, and an interrupter for breaking said circuit.

In witness whereof, I hereunto subscribe 20
my name this 3rd day of March, 1922.

WILLIAM W. HAWKINS.
